UNITED STATES PATENT OFFICE.

GUY M. GEST, OF CINCINNATI, OHIO.

COMBINED CURB AND GUTTER.

SPECIFICATION forming part of Letters Patent No. 739,854, dated September 29, 1903.

Application filed July 12, 1902. Serial No. 115,313. (No model.)

To all whom it may concern:

Be it known that I, GUY M. GEST, a citizen of the United States, and a resident of Cincinnati, in the county of Hamilton and State 5 of Ohio, have invented certain new and useful Improvements in a Combined Curb and Gutter, of which the following is a specification.

My invention relates to combined street 10 curbs and gutters; and its primary object is to provide a combined curb and gutter of an improved form and made up of connected sections of vitrified material.

A further object of the invention is to provide 15 combined curb and gutter sections of vitrified material and improved means for securing said sections together.

With these ends in view the invention consists of combined curb and gutter sections of 20 an improved form and made of vitrified material and of any preferred length and the improved means hereinafter described for securing the meeting ends of such sections together.

25 The construction of the improvement will be fully described hereinafter in connection with the accompanying drawings, which form part of this specification, and its novel features will be particularly pointed out in the 30 appended claims.

In the drawings, Figure 1 is a view in perspective of a combined curb and gutter section embodying the invention. Fig. 2 is an elevation of parts of two sections connected 35 together, the connecting means being shown in dotted lines. Fig. 3 is a detail perspective view of a metallic strap employed for securing the sections together at their meeting ends. Fig. 4 is a perspective view of a modified embodiment of the invention; and Fig. 40

5 is a front elevation of the two sections shown in Fig. 4 connected, the connecting means being shown in dotted lines.

Corresponding parts in all the figures are 45 denoted by the same reference characters.

Each of the sections comprises a curb member and a gutter member, said members being integral one with the other and preferably made of vitrified material. All of the 50 external angles of each section are preferably right angles. The upper face of the gutter member is horizontal for a part of its width

and thence curves upwardly and toward the curb member to meet a vertical face of the curb member 2. From said vertical face the 55 surface of the curb member curves upwardly and outwardly and meets the back vertical face at an upper and outer angle 4 of said curb member. Thus, as will be seen, each section is bounded transversely by arcs of 60 two circles and five rectangularly-arranged faces, three of which are vertical and two horizontal, as before described and as shown in the drawings, and for the purposes of this specification a combined curb and gutter section, which is formed transversely, as thus described and shown, will be termed herein a "combined curb and gutter section" A. Each of the sections is formed at its ends with a recess 5, extending from the inner surface 65 of the curb portion 2, just below the top thereof, to a point near the outer side of the gutter portion 1. When the ends of two of the sections are placed together, their recesses 5 register with each other and together form a pocket 70 to receive a connecting-strap 6, of sheet metal, and preferably perforated, as shown in Fig. 3. The connecting-strap is of a shape corresponding to the shape of the recess and is adapted to be first fitted into the recess of 75 one of the sections, after which the adjacent section is fitted upon the projecting portion of the strap. Thus it will be seen that the connecting-strap overlaps both of the sections, forming a splice-joint. After the connecting-strap is in position cement or like sealing material is poured into the space containing the strap through the opening 7. The cement surrounds the strap and also enters the perforations therein, so that when it is 80 set a secure water-tight joint is insured.

In Figs. 4 and 5 I have shown a modified construction, in which one of the sections 8 is formed with one or more end recesses 9 and the adjacent section 10 with tongues or flanges 95 11, fitting within or overlapping the recessed portions of the section 8. This manner of connecting the meeting ends of the sections may be employed either as supplementary to the splicing-strap or as a substitute for the latter. The advantages of the peculiar transverse form of a curb and gutter formed of my improved combined curb and gutter sections A will be readily understood. When prop-

erly placed in the positions in which the sections A are particularly designed to be used—such, for instance, as in streets which comprise a carriage-way with a sidewalk at one or each side thereof—the upper surface of the curb member should be flush with the surface of the sidewalk and the upper surface of the gutter member should not be higher than the surface of the contacting parts of the pavement of the carriage-way. The latter, being properly "crowned" or transversely convex in form, will shed liquid substances therefrom into the gutter members. It should also be noted that the convexity of the form of the upper and outer part of the curb member will prevent the crumbling of the material of the latter by the wheels of vehicles which may be backed against the curb or contact the latter at an obtuse angle, while the concave form of the surface which leads from the curb member to the gutter member will prevent injury to the curb member, such as might be caused by the wheels of vehicles contacting the curb member at an acute angle.

25 The utility of the invention will be readily appreciated. The integral sections A may be manufactured in suitable lengths, and by merely joining and securing the ends in the manner described a continuous combined 30 curb and gutter is constructed.

The invention comprehends and includes all such variations and modifications in form and structure as may fall within the terms and scope of the following claims.

35 Having thus described my invention, I claim and desire to secure by Letters Patent—
1. A curb and gutter section of vitrified material having a horizontal and a vertical leg and a recess in each end extending from a point adjacent the end of the horizontal or gutter leg to the upper portion of the vertical or curb leg and opening externally at said upper end.

2. The combination with a curb and gutter 45 section of vitrified material having a horizontal and a vertical leg and a recess in each end

extending from a point adjacent the end of the horizontal leg to the upper portion of the vertical leg and opening at the side of said upper leg, with a perforated key member 50 adapted to be inserted within the said recesses in adjacent sections and to be secured therein by cement.

3. A combined street curb and gutter, comprising integral sections of vitrified material, 55 having recesses at their ends, and a perforated metallic strap fitting within the space formed at the meeting ends of the sections by the registering recesses.

4. A combined curb and gutter, comprising a plurality of integral sections of vitrified material formed with end recesses, a perforated metallic strap interposed between the meeting ends of the sections and fitting within the space formed by the registering recesses, and a filling of cement or like material to insure a water-tight joint between the sections.

5. A combined curb and gutter, comprising a plurality of integral sections A, made 70 of vitrified material and formed with registering end recesses; overlapping flange connections connecting said sections; a perforated metallic strap interposed within the space formed by the registering recesses; and 75 sealing material surrounding the metallic strap within the recesses.

6. As an article of manufacture, an integral section of vitrified material comprising a horizontal gutter portion, and a vertical curb portion, and formed with end recesses extending downwardly from the inner face of the curb portion to, and terminating at a point near and within the outer side of the gutter portion.

In testimony whereof I have signed my name in the presence of the subscribing witnesses.

GUY M. GEST.
